UNITED STATES PATENT OFFICE.

OTTO P. ROHR, OF SEATTLE, WASHINGTON.

HYDRAULIC MOTOR AND THE LIKE.

1,100,914.

Specification of Letters Patent. Patented June 23, 1914.

Application filed February 20, 1913. Serial No. 749,644.

To all whom it may concern:

Be it known that I, Otto P. ROHR, a subject of the King of Norway, and a resident of the city of Seattle, in the county of King 5 and State of Washington, have invented certain new and useful Improvements in Hydraulic Motors and the like, of which the following is a specification.

My invention has particular reference to 10 apparatus of the above type operated through pressure of the fluid, and has for one of its objects to provide novel mechanism wherein a prime mover, or piston is mounted for movement in a runway composed of a plurality of sections through 15 which the fluid flows to drive the piston.

A further object resides in the provision of mechanism for controlling the fluid in the runway sections.

20 Other objects will be set forth as my description progresses and those features of construction, arrangements and combinations of parts on which I desire protection, succinctly defined in my annexed claims.

25 Referring to the accompanying drawing wherein like numerals of reference indicate like parts throughout: Figure 1 is a horizontal section of my apparatus. Fig. 2 is a vertical section taken on line 2—2 of Fig. 1.

30 Referring to the drawing by numerals of reference, 1 indicates a casing having an internal chamber 2 encircled by a runway 3 and communicating therewith through an opening or passage 10. In runway 3 a 35 piston or prime member 4 is arranged for operation.

Casing 1 is provided with fluid inlet ports 1', 1'', whose inner end portions are enlarged, as at 1^a, so that valves 6, which 40 divide runway 3 into sections 3^a, 3^b, when opened, as shown by dotted lines in Fig. 1, will not cut-off the ingress of water.

I provide mechanism under control of piston 4 for controlling passage 10 so that 45 the water is alternately confined in and permitted to discharge from a runway section. Such mechanism comprises a valve or closure 11, which is substantially the shape of a half disk fixed to piston 4. As now considered, I prefer to fit valve 11 in passage 10, this arrangement being simple and enabling me to connect piston 4 to a shaft 13 through the medium of a perforated web portion 12, as clearly shown.

55 While this construction and arrangement of parts just described, is simple, durable

and compact, it can be readily modified without departing from the spirit of my invention, defined in my annexed claims.

With valve 11 arranged as described, outlet passage 10, which must be continuous, consists of the space between cylindrical alining extensions 2' of casing heads 7 and 8, which extensions form the side wall of chamber 2. Valve 11 is of sufficient peripheral length to entirely or practically entirely close a section of runway 3, as shown in Fig. 1. Piston 4 is on one end of valve 11. Therefore, as piston 4 passes a valve 6, valve 11 gradually opens the runway section just left to relieve back pressure on the other valve 6 and closes the present runway section at the rear of the piston to confine the water flowing through the adjacent inlet port. Further, it will be observed that that 75 portion of the runway forward of the piston is open to exhaust, as is also the succeeding runway section. The water or fluid after passing through the passage 10 on opening of the latter by the valve 11, passes to either 80 side of said valve within the chamber 2 and thence out through the perforated head 7. Valves 6 are slightly curved in cross-section and provided with trunnions 16 journaled in heads 7 and 8, and have bearing in seats 16^a 85 of casing 1 at the forward side of the enlarged ends 1^a, of the inlet ports. They further preferably abut the cylindrical extensions 2'.

To obtain a more efficient driving action 90 of water on the piston I form the rear face of the latter concave and inclined forwardly in an outward direction so that it and the adjacent face of a valve 6 will converge toward shaft 13 when the piston is moving 95 past an inlet port. The forward face of piston 4 is convex and inclined rearwardly in an outward direction. Therefore, only the free end portion of a valve 6 will engage the piston during the opening movement of the valve, thus riding over the face of the piston to permit of the passage of the latter from one runway section to the other. Shaft 13 projects through head 8 and is conveniently provided with a pulley 20. 100

While I have herein described my invention as particularly adapted as a water motor and piston 4 to be driven by the fluid to operate a shaft from which the desired power is taken, it will be understood that I 110 do not wish to be understood as limiting my invention to this particular adaptation.

Having thus described my invention, what I claim as new, and desire to secure by Letters Patent of the United States of America, is:—

- 5 1. In mechanism of the character described, a continuous runway divided into sections each having an inlet passage and an outlet passage, valves controlling communication between the sections of said runway, a piston in said runway and means operated by said piston to gradually open the exhaust passage of one runway section during advance movement of said piston in the preceding runway-section.
- 10 2. In mechanism of the character described, a continuous runway divided into sections each having an inlet passage and an outlet passage, valves controlling communication between the sections of said runway, a piston in said runway and means operated by said piston to gradually open the exhaust passage of a runway section following movement of said piston from such section.
- 15 3. In mechanism of the character described, a casing provided with an internal chamber, a continuous runway extending about the internal chamber of said casing, said runway being divided into sections each having an inlet passage and an outlet passage, the outlet passage of said runway sections communicating with the chamber of said casing, valves controlling communication between the sections of said runway, a piston in said runway and means operated by said piston for alternately closing the outlet passages of said runway sections.
- 20 4. In mechanism of the character described, a casing, a continuous runway in said casing divided into sections, a chamber in said casing lying inwardly of the said runway and provided in its wall with means for establishing communication between said chamber and the runway sections, valves controlling communication between the runway sections, a piston in said runway, and means movable with said piston for controlling the exhaust means of said chamber for cutting off from exhaust that portion of a runway section between the piston and the inlet port of the section in which the piston is operating and opening to exhaust that portion of such runway section lying forwardly of the piston.
- 25 5. In mechanism of the character described, a casing, a continuous runway in said casing divided into sections, a chamber in said casing lying inwardly of the said runway and provided in its wall with means for establishing communication between said chamber and the runway sections, valves controlling communication between the runway sections, a piston in said runway, and means movable with said piston for controlling the exhaust means of said chamber for cutting off from exhaust that portion of
- 30 a runway section between the piston and the inlet port of the section in which the piston is operating and opening to exhaust that portion of such runway section lying forwardly of the piston, and then opening to exhaust the next runway section prior to the entrance of the piston therein.
- 35 6. In mechanism of the character described, a casing, a continuous runway in said casing divided into sections each of which has its own intake and exhaust passages, valves controlling communication between the sections of said runway, a piston in said runway, and means movable with said piston for controlling communication between a section and its exhaust passage to successively open to exhaust the front portion of a runway section in which the piston is moving and then the succeeding runway section in advance of the entrance of the piston therein.
- 40 7. In mechanism of the character described, a casing, a continuous runway in said casing divided into sections each of which is provided with intake and exhaust passages, valves controlling communication between the sections of said runway, a piston movable in said runway, and valve means movable with said piston for simultaneously maintaining open to exhaust the runway sections on opposite sides of and in advance of a valve and further maintaining closed to exhaust that portion of the runway section lying between the piston and the section inlet port.
- 45 8. In mechanism of the character described, a casing provided with a runway, an internal chamber opening into said runway and forming a delivery passage therefor, valves in the runway of said casing and dividing the same into sections, inlet ports for each of the said runway sections, a piston in said runway, and valve means controlling the communication between said runway and said internal chamber movable with said piston.
- 50 9. In mechanism of the character described, a casing, a runway in said casing, an internal chamber at the inner side of said runway, said chamber having its wall formed with a passage for the delivery of water from the runway, valves in said runway dividing the same into sections, inlet ports for the sections of said runway, a piston in said runway, and a closure means for the passage of said chamber wall movable with said piston to alternately close the runway sections to communication with said chamber.
- 55 10. In mechanism of the character described, a casing, a continuous runway in said casing, valves dividing said runway into sections, inlet ports for the sections of said runway communicating therewith in proximity to said valves, a piston in said

runway, said valves being arranged to be engaged and moved by said piston to permit of the passage of the latter, an outlet passage for said runway, and means operated by said piston for opening and closing said outlet passage.

11. In mechanism of the character described, a casing having an internal cylindrical wall formed with a continuous opening, a runway in said casing extending about said cylindrical wall, valves in said runway, means for admitting fluid to said runway, a piston in said runway, and closure means for the opening of said cylindrical wall normally covering only a portion of said opening and being movable with said piston.
12. In mechanism of the character de-

scribed, a casing having an internal cylindrical wall formed with a continuous opening, a runway in said casing extending about 20 said cylindrical wall, valves in said runway, means for admitting fluid to said runway, a piston in said runway, closure means for the opening of said cylindrical wall extending through said opening and normally closing 25 only a portion thereof, said piston being fixed to said closure, and a shaft within said cylindrical wall fixed to said closure.

Signed at Seattle, Washington, this 10th day of February, 1913.
